UNITED STATES PATENT OFFICE.

OTIS A. MYGATT, OF NEW YORK, N. Y.

DESIGN FOR A PRISMATIC-GLASS REFLECTOR.

No. 38,026.

Specification for Design.

Patented May 22, 1906.

Application filed March 9, 1906. Serial No. 305,183. Term of patent 14 years.

To all whom it may concern:

Be it known that I, OTIS A. MYGATT, a citizen of the United States, residing at New York, in the county of New York and State of New York, have invented a new, original, and ornamental Design for Prismatic-Glass Reflectors, of which the following is a specification, reference being had therein to the accompanying drawings, forming part thereof.

Figure 1 is a top plan of a reflector embodying my design. Fig. 2 is a bottom plan thereof.

The body of the reflector is in form of a star, with its upper surface below the collar

covered with reflecting-prisms arranged as shown in Fig. 1. The inside of the reflector is smooth; but the prisms show through in brilliant lines or facets, which are merely indicated in dotted lines in Fig. 2. The inside of the reflector is much more brilliant than the outside.

I claim—

The ornamental design for a prismatic-glass reflector as shown and described.

OTIS A. MYGATT.
